DEODORIZER OR THE LIKE

Arthur N. Wells, Belmont, Calif.

Application October 1, 1953, Serial No. 27,051

Term of patent 14 years

(Cl. D16—2)

Fig. 1.

Fig. 2.

To all whom it may concern:

Be it known that I, Arthur N. Wells, a citizen of the United States and a resident of the city of Belmont, State of California, have invented a new, original, and ornamental Design for a Deodorizer or the like, of which the following is a specification, reference being had to the accompanying drawing, forming a part thereof.

Fig. 1 is a front view of a deodorizer or the like embodying my new design.

Fig. 2 is a front perspective view thereof. The back portion not shown is substantially flat.

I claim:

The ornamental design for a deodorizer or the like, as shown and described.
